COMBINED WATER CONTROL HANDLE AND ESCUTCHEON FOR A BATHTUB OR THE LIKE

Ralph La Rue Du Bois, 4242 E. 111th St.,
Tulsa, Okla. 74135

Continuation-in-part of abandoned design application Ser.
No. 22,944, May 13, 1970. This application July 12,
1971, Ser. No. 161,378

Term of patent 14 years

Int. Cl. D23—01
U.S. Cl. D23—31

FIG. 1.

FIG. 2.

FIG. 1 is a front elevational view of a combined water control and escutcheon for a bathtub or the like showing my new design; and

FIG. 2 is a side elevational view thereof with a portion broken away for convenience of illustration.

I claim:

The ornamental design for a combined water control handle and escutcheon for a bathtub or the like, substantially as shown.
